UNITED STATES PATENT OFFICE.

HOWARD C. HEINZ, OF PITTSBURG, PENNSYLVANIA.

DESIGN FOR A BOTTLE.

SPECIFICATION forming part of Design No. 34,712, dated July 2, 1901.

Application filed April 10, 1901. Serial No. 55,256. Term of patent 14 years.

To all whom it may concern:

Be it known that I, HOWARD C. HEINZ, a citizen of the United States, residing at Pittsburgh, in the county of Allegheny and State of Pennsylvania, have invented and produced a certain new, useful, and original Design for Bottles, of which the following is a specification.

In the accompanying drawings, forming a part of this specification, Figure 1 is a side elevation of a bottle embodying my new design, and Fig. 2 is a sectional plan on a plane indicated by the line II II, Fig. 1.

The leading or characteristic feature of my design consists in a shape or configuration of the bottle consisting of a substantially angu-

lar body portion and a tapering neck extending from the body portion. The bottle is divided into sections 2 by a series of ribs 1. Portions of the sections or panels are flattened, as shown at 3, giving to the body portion a substantially polygonal shape.

I claim herein as my invention—

The design for a bottle, as herein shown and described.

In testimony whereof I have hereunto set my hand.

HOWARD C. HEINZ.

Witnesses:

F. E. GAITHER,
F. M. DAPPER.
